UNITED STATES PATENT OFFICE.

PHILIP J. MEAHL, OF SUMMIT, NEW JERSEY, ASSIGNOR TO AMERICAN PIANO COMPANY, OF NEW YORK, N. Y., A CORPORATION OF NEW JERSEY.

MUSIC-ROLL-PRINTING MACHINE.

Application filed May 5, 1920. Serial No. 378,997.

To all whom it may concern:

Be it known that I, PHILIP J. MEAHL, a citizen of the United States, and a resident of the city of Summit, in the county of Union and State of New Jersey, have invented an Improvement in Music-Roll-Printing Machines, of which the following is a specification.

This invention relates to improvements in machines for marking perforated music rolls such as are used on automatic or semi-automatic music playing devices.

One of the objects of this invention is to provide a machine which will properly print characters on a music sheet, and which has the characters removable or adjustable on a moving part of the machine. Other objects of the invention will be apparent from the following detailed description.

The drawing which accompanies and forms a part of this disclosure is of a preferred form selected for purposes of illustration, wherein:

Figure 1 is a side view of the printing machine; Figure 2 is a view of part of the adjusting arrangements for the impression roller;

Figure 3 is a top plan view of the printing machine;

Figure 4 is a view of one of the type set holders;

Figure 5 is a section of a holder taken on the lines 5—5 of Figure 4;

Figure 6 is a view of one of the type sets;

Figure 7 is a section of a type set taken on the line 7—7 of Figure 6;

Figure 8 is a view of the conveyer showing the holders and trips;

Figure 9 is a section of the conveyer on the line 9—9 of Figure 8;

Figure 10 is a section of the belt and trip taken on the lines 10—10 of Figure 9;

Figure 11 is a side view of one of the catches in normal position;

Figure 12 is a view of the same catch after tripping;

Figure 13 is a side view of the frame and impression roller in normal operating position;

Figure 14 is a view of the impression roller in non-operating position;

Figure 15 is a view of the brake mechanism when the machine is operating; and

Figure 16 is a view of the brake as applied.

In the printing art, especially as applied to operations in connection with placing characters on music sheets which are used on automatic or semi-automatic musical instruments, it has been exceptionally difficult to place such characters at required positions, especially where characters which include words or syllables must be placed in line with certain perforations in the music sheet. Heretofore such characters have been placed by forming a pattern of paper with the characters forced or raised from the surface of the pattern which is then brought into contact with the music sheet. This method is undesirable as it necessitates a new sheet or pattern for each song and the raised characters soon become worn and destroyed. One of the objects of this invention is to provide a means for bringing into contact with the music sheet, type which is adjustable as to position and which permits printing of a great number of music sheets without wearing.

Referring now to Figure 1 in the drawings the machine 1 has frame 2 carrying a wheel 3 which receives a conveyer 4. An idle wheel 5 is mounted on frame 6 and also receives the conveyer and is adjustable in position to vary the tension on the conveyer. A music sheet 7 is drawn from the supply rack 8 and is carried by impression roller 9 mounted in the frame 10 which is pivotally mounted at 11. A presser roller 12 is mounted on the frame 2 and biased in position against the impression roller by a spring 13. The music sheet moves between the two rollers and has a linear speed equal to that of the conveyer so that the music sheet may be brought into contact with the type sets carried on the conveyer. A weight 14 is pivoted at 15 on the supply rack and contacts with the music sheet to hold it taut between the rack and the impression roller. A rack 16 receives the music sheet after it passes beyond the presser roller. Rollers 17 on the rack 16 are provided with short belts 18 preferably made of canvas and may be driven at various speeds, generally at a little higher rate than the speed of the music sheet so that there will be a tendency to pull the music sheet from the printing machine. It is preferable, however, to have the belts farthest away from the printing machine moving at a greater rate of speed than the belts nearer.

Power is applied to the machine by motor 19 which is pivoted at 20 and the pulley 21 of the motor drives the wheel 3. Power is distributed from shaft 21' upon which wheel 3 is mounted to the various parts of the machine as is clearly illustrated in Figure 3. Shafts carry reducing gears 22 which transmit power to chains 23 and from there to the impression roller and to the inking rollers 24. Preferably, the power is transmitted through chains, and idle pulleys are employed so that there will be no lost motion when the machine stops.

The conveyer which carries the type sets 15 may be of any suitable form or material and is herein shown as being made of such suitable material that is substantially non-extensible. The longitudinal strains in the conveyer are low as the resistance to the 20 movement of the conveyer during the operation of the machine is very small. The characters to be printed are preferably formed on a bar 25 which has the type syllable or letter 26 formed thereon. These 25 characters may be of one or more letters or figures. This bar with the characters thereon, for the purposes of description and reference in the claims, will hereinafter be referred to as a type set or type units. 30 Means are provided to hold the type sets on the conveyer such as holders 27 which are held in position by rivets 28. The ends of the holders are turned back on themselves as illustrated at 29 and 30, and the 35 extreme edges are corrugated at 31 to receive the type sets. The two ends of the type set are cut down and slotted at 32 so that the ends thereof may be properly adjusted and held in the holders 27. Referring 40 particularly to figure 8, there is disclosed a holder with a type set properly placed therein and the section of the type set as shown in figure 9 taken with the disclosure in figure 6 clearly illustrates one of 45 the type sets and the method of positioning it in the holders. In preparing the conveyer for use in the machine, the position of the perforations and the words or characters which are to be placed opposite certain 50 perforations, are carefully noted and the type sets placed in the holders so that the conveyer as it moves in synchronism with the music sheet carries the characters or words into printing relation with the 55 music sheet and opposite the proper perforations.

During operation the conveyer contacts with the outer surface of wheel 3 so that 60 openings 33 in the conveyer receive teeth 34 which are mounted on the wheel and a positive drive of the conveyer results. Mounted on the shaft of the impression roller is a ring 35 which contacts with the conveyer. The impression roller itself, which carries 65 the music sheet, is adjustable relatively to

the ring 35. This adjustment provides for the positioning of the impression roller in respect to the height of the type. Knob 36 when pushed inwardly operates a clutch so that the impression roller proper may be 70 rotated irrespective of the chain drive mechanism. The impression roller and ring may be adjusted in the frame by means of set screws 37 and 38 as noted in Figures 2 and 3. This adjustment provides for the 75 position of the impression roller when conveyers are of various thicknesses.

In operating the machine, a predetermined mark on the music sheet is brought in contact with the presser roller and the impression roller is oscillated to normal operating position. The brake on the wheel 3 is removed by pressing the foot lever 39, and the pulley 21 of motor 19 is moved into contact with the wheel 3 by pressing the 80 foot lever 40 thereby driving the wheel 3 which positively moves the conveyer belt. The motion from the foot pedal 39 is transmitted through a link 39' to a lever 40', one end of which engages a collar 41' mounted 85 on a rod 42'. This rod is normally pushed downwardly by a spring 43', which is connected at the common pivot point of a toggle 44', which toggle is at one end 45' pivoted to the frame of the machine and at the other end 46' to a lever 47'. The latter lever is pivoted at 48' to the brake shoe 47 and at 49' to the frame of the machine. The rod 42' is normally held in an upward position with the spring 43' compressed and the shoe 47 withdrawn from the wheel 3 by the engagement of a lock 50' which is pivoted to the lower end of the trip 44, and engages beneath the collar 41'. The spring 51' tends to maintain the lock 50' in engagement with the collar 41', but its action is destroyed by the movement of the trip 44 which releases the lock 50' and permits the downward movement of the rod 42' and the operation of the brake shoe. A link 52' 100 is connected to the base of the motor 19, is slidably connected by slot-and-pin engagement 53' with the frame of the machine, and is normally held in its uppermost position so that the pulley 21 on the armature shaft of the motor is held in engagement with the wheel 3. The weight 45 operating on the link 52' moves the motor 19 about its pivot 20 and disengages the pulley 21 105 from the wheel 3 when the trip 42 is disengaged from the upper end of the link 52'. Power is also transmitted through the reduction gears 22 and the chain drives to the impression roller and to the inking rollers. The reduction gears are adjusted so that the 110 speed of the impression roller is in synchronism with the speed of the conveyer, and the music sheet is carried into contact with the type sets so that characters are printed 115 opposite proper perforations or at proper 120 125 130

places on the music sheet. After all of the characters have been printed on the music sheet the machine is brought to a stop and the impression roller oscillated to a remote 5 position from the conveyer.

In bringing the machine to rest the trips 41 mounted on the conveyer are brought into contact with catches 42, 43, and 44 successively and these catches release respectively the motor from the driving wheel by the dropping of weight 45; releases the weight 46 which oscillates the impression roller; and releases a brake catch which allows brake 47 to move against wheel 3 so 10 that the conveyer is stopped in a predetermined position in order that it may, upon starting the next time, print the characters in the proper places on the next music sheet. The trips 41 have lugs 48 which extend 15 through openings 49 in the conveyer so that the lugs will contact with the catches which are adapted to extend through openings. A presser bar 50, being part of the frame 2, is positioned to force the lugs through the 20 conveyers and to maintain them in contact with the catches. The three catches may be placed at any desired position on the frames and the positioning of the trips on the conveyer will operate the catches at predetermined intervals. It is to be understood that one trip may be substituted for a plurality of trips and in such a case the 25 positioning of the catches on the frame of the machine will determine the intervals at which the trip will properly operate the catches. It is, however, to be understood that this may have three separate catches for the operation of the various mechanisms of this machine or they may be 30 combined in one so that it may perform the various functions.

It will be understood that the embodiment of the invention herein described and shown in the accompanying drawings may be variously modified, and that the present invention is susceptible of different embodiments. In so far as such modifications and embodiments of the invention come within the scope of the following claims they are considered 45 to be within the scope of the invention.

I claim:

1. In a printing machine the combination

of a conveyer having type sets and trips thereon, an impression roller pivotally mounted and adapted to be closely associated with said conveyer, and catches in said machine to be operated by said trips to release the driving power to allow oscillation of said impression roller and the application of a brake to stop the movement of said conveyer. 55

2. In a printing machine the combination of a conveyer having type sets and trips thereon, an impression roller pivotally mounted and adapted to be closely associated with said conveyer, and catches in said machine to be successively operated by said trips to release the driving power to oscillate the compression roller and to apply a brake to stop the movement of said conveyer. 60

3. In a printing machine the combination of a conveyer having openings therein said conveyer adapted to carry type sets and trips, a wheel engaging with said conveyer and having teeth thereon for entering said openings, means for inking said type sets, an impression roller pivotally mounted on said machine, a presser roller mounted on said frame and adapted to contact with said impression roller and having a music sheet associated therewith and with said impression roller and adapted to be brought in contact with said type sets, catches on said machine operated by said trips, a presser bar 75 for holding said trips in contact with said catches, means for moving the driving power after the operation of said catches, means for moving said impression roller away from said conveyer, means for applying a 80 brake to said wheel to stop said conveyer, and means for moving said music sheet away from said machine. 85

4. In a printing machine the combination of a holder adapted to be mounted on a conveyer and having corrugated edges, a type set having a letter thereon and adapted to be held by said holder and to receive a portion of the corrugations. 95

In testimony whereof, I have signed my 100 name to this specification this 3rd day of May, 1920.

PHILIP J. MEAHL.
